UNITED STATES PATENT OFFICE.

WILLIAM J. GLOVER, OF NOBLE, TEXAS.

CHIMNEY.

SPECIFICATION forming part of Letters Patent No. 625,756, dated May 30, 1899.

Application filed August 30, 1898. Serial No. 689,832. (No model.)

To all whom it may concern:

Be it known that I, WILLIAM JEFFERSON GLOVER, a citizen of the United States, residing at Noble, in the county of Lamar and State of Texas, have invented certain new and useful Improvements in Chimneys; and I do declare the following to be a full, clear, and exact description of the invention, such as will enable others skilled in the art to which it applies to make and use the same.

My invention relates to a novel form of smoke-flue or chimney; and the object is to provide a simple, durable, and practically fireproof flue of this character for dwellings, stores, and all other forms of buildings requiring a device of this kind.

To this end the invention consists in the construction, combination, and arrangement of the device, as will be hereinafter more fully described, and particularly pointed out in the claim.

Figure 1 is a perspective view of my improved flue with a portion of the roof broken away to show the manner of fixing the flue in place. Fig. 2 is a vertical longitudinal section of the same. Fig. 3 is a perspective detail of the contiguous faces of two of the sections separated.

1 denotes the roof of the structure, and 2 2 the parallel girders. 3 3 represent parallel cross-braces fixed to the upper sides of said girders, and 4 represents the base-section of the flue or chimney, formed with the lateral flanges 5 5, which are secured to said braces 3 3 by means of the bolts 6 6, the heads of the bolts being connected by a plate 7, on which the flanges 5 5 rest, while the lower rectangular depending socket 8 extends flush with

or projects through the ceiling of the apartment to receive the stovepipe 9.

10 10 denote transverse braces connecting the cross-braces 3 3 and on which the next flue-section 12 rests in such a manner that its lower face will form a joint with the upper face of the base-section 4.

13 14 15 16 17 18 19 20 21 represent the superimposed flue-sections terminating in the cap-stone 22, the entire series being formed with centrally-alined orifices, as shown, which constitute the flue or smoke-passage.

The contiguous faces of each of the sections are formed with a contiguous groove 23 and with a recess 24, so that when the sections are assembled a layer of cement or other suitable binding material may be placed between to cement the whole into one rigid column.

Having thus fully described my invention, what I claim as new and useful, and desire to secure by Letters Patent of the United States, is—

The combination with the girders, the cross-braces and the transverse braces connecting said cross-braces, of the base flue-section 4 formed with the lateral horizontal flanges 5 5, the plates 7 7 and the supporting-bolts 6 6 connecting said plates, base-section and cross-braces, and the superimposed flue-sections, substantially as shown and described.

In testimony whereof I have hereunto set my hand in presence of two subscribing witnesses.

W. J. GLOVER.
